UNITED STATES PATENT OFFICE.

JAMES F. ATWOOD, OF BOSTON, MASSACHUSETTS.

BUTTON.

SPECIFICATION forming part of Letters Patent No. 298,154, dated May 6, 1884.

Application filed October 10, 1883. (No model.)

To all whom it may concern:

Be it known that I, JAMES F. ATWOOD, of Boston, in the county of Suffolk and State of Massachusetts, have invented new and useful 5 Improvements in Buttons, of which the following is a specification.

This invention relates to that class of buttons provided with shanks, but not to that class having wire loops, sometimes termed 10 "shanks." The object is to provide a passage in the shank which will be adapted to accommodate a wire fastening without injury to the latter.

In the accompanying drawings, in which 15 similar letters of reference indicate like parts, Figure 1 is a view in perspective of a button embodying my invention. Fig. 2 is a vertical section of the same. Fig. 3 is a similar section with the fastening-wire in position. 20 Fig. 4 is a sectional view of the cup C detached.

A is the body of the button, constructed, as usual, of upper and under plates, *a* and *a'*, formed into the shape shown. The shank is 25 composed of the external tube, B, spread into a flange, B', at its lower end, and the inner cup, C, having its bottom C' convexo-concave in shape, as shown. Both the tube B and the 30 cup C are clinched by means of suitable machinery against the inner surface of the portion *a* of the button in the well-known manner, as shown.

In order to provide a passage for the fastening-wire D, vertical slots are cut on opposite 35 sides of the tube B at *b*, said slots commencing

with the lower end or flanged portion of said tube and extending upward toward the point, where the portion *a'* of the button joins the shank. Openings are also cut at opposite sides of the cup C at *c*, which coincide with the slots 40 *b* in the tube B.

By means of the convexo-concave bottom C' to the cup C the wire D, when drawn tightly against it, as it would be in practice, is curved, but not sharply bent, and hence is not liable 45 to be broken. The button is also given freedom of action without changing the bend in the wire.

Having thus fully described my invention, what I claim, and desire to secure by Letters 50 Patent, is—

1. The herein-described button, provided with a hollow shank whose bottom or outer end is pressed inwardly into convexo-concave shape, as shown and described, said shank being provided with a transverse passage or perforation, whereby a wire for fastening purposes may be drawn through the latter and over the said bottom or end, substantially as 55 and for the purpose specified. 60

2. In a button, the combination of the outer tube, B, of the shank, provided with the opposite vertical slots, *b*, and the inner cup, C, provided with the coincident opposite openings, *c*, and convexo-concave bottom C', substantially as and for the purpose described. 65

JAMES F. ATWOOD.
